UNITED STATES PATENT OFFICE.

JOSEPH PERCY REMINGTON, OF PHILADELPHIA, PENNSYLVANIA.

TABLET-ASSEMBLING DEVICE.

1,277,121.

Specification of Letters Patent. Patented Aug. 27, 1918.

Original application filed April 1, 1913, Serial No. 758,237. Divided and this application filed January 22, 1915. Serial No. 3,805.

To all whom it may concern:

Be it known that I, JOSEPH PERCY REMINGTON, a citizen of the United States, residing in Philadelphia, Pennsylvania, have invented certain Improvements in Tablet-Assembling Devices, (being a division of my application for patent filed April 1, 1913, Serial No. 758,237,) of which the following is a specification.

10 One object of my invention is to provide a device for sorting and re-arranging tablets delivered in mass to a hopper, so that they will be discharged in straight lines each containing a predetermined number 15 ready for insertion in a box or package.

Another object of the invention is to provide a machine of the above noted type with novel means for continuously assembling predetermined numbers of tablets in the 20 form of successive charges for filling boxes carried by a suitable magazine, said invention contemplating means for separating the powder and broken tablets from the perfect tablets prior to their assembly.

25 The invention further includes novel means for receiving a mass of tablets and thereafter assembling and condensing them so that they are delivered in the form of a series of rows each consisting of a predetermined 30 number of tablets lying parallel with each other.

These objects and other advantageous ends I secure as hereinafter set forth, reference being had to the accompanying drawings in which:—

35 Figures 1 and 1^a together are a side elevation illustrating my invention as constructed for use in connection with a packaging machine;

40 Fig. 2 is a rear elevation of the machine shown in Fig. 1.

Fig. 3 is a vertical section of part of the structure shown in Fig. 1 and on a somewhat enlarged scale.

45 Fig. 4 is a plan of the apparatus shown in Fig. 3.

50 Figs. 5 and 6 are respectively a perspective view and a transverse section of the tablet assembling device, the latter being taken on the line c—c, Fig. 4.

Fig. 7 is an enlarged perspective view of the tablet condensing device.

Fig. 8 is a vertical section illustrating a detail of the invention.

Figs. 9 and 10 are perspective views illustrating the detail construction of the tablet transferring mechanism.

Fig. 11 is a section on the line b—b, Fig. 3, and

Fig. 12 is a fragmentary vertical section further illustrating the detail construction of certain parts of my invention.

In the above drawings 6 represents a table for the reception of tablets as they are delivered from a tablet making machine or other source of supply, and this is provided with a perforated plate 7, set flush with its top surface and having mounted under it a drawer 8 in position to catch dust or small broken pieces separating from the mass of tablets on the table, it being understood that the latter are agitated or moved by the operator over said plate prior to their delivery to a chute 9. This chute projects above the table surface at the sides and back of the opening formed therein for its reception and extends downwardly below the table where its lower end is slidably engaged by the upper end of a hollow arm or conduit 20. The lower end of this arm is provided with a lateral cylindrical extension 21 on which is journaled one end of an elongated oscillatory container 19, which at its forward end is hinged or pivoted to a supporting frame 14 by means of a pivot spindle or pin 22, the arrangement being such that the tablets delivered to the hollow arm 20 find their way into the container 19, through the lateral extension 21 which has an inclined deflecting portion 21^a to facilitate this movement of the tablets. The ends of the container 19 are preferably rounded or made semi-cylindrical in section as shown in Fig. 3, and its bottom, though cut away at the middle, has portions 23 and 24 at its opposite ends on which the tablets may temporarily rest.

Below the bottom and permanently attached in any suitable manner to the body of the container 19 is an assembling trough 100 25 consisting of a shallow box within which are mounted two series of thin vertically set parallel plates or partitions 26 and 27 extending from one end of said trough to the

other. The portions of the plates under the part 24 of the bottom of the container 19 are all of the same height, but the remaining parts have their upper edges extended 5 through the opening above the bottom of said container as indicated at 28 in Fig. 5, the extensions of alternate ones of said plates 27 being gradually inclined upwardly from the edge of the bottom part 24 and thereafter descending abruptly to the closed 10 end 29 of the trough 25, while the remainder are inclined upwardly with comparative abruptness from the part 24 and thereafter descend gradually toward the end 29 of said 15 trough.

A condensing and delivery trough 30 extends downwardly from the hinge or pivot 22, which with it is rigidly supported by 20 the frame, as shown in Figs. 1 and 3, and this trough consists of an inclined plate having sides 31, which while parallel at the upper end of said plate, converge as they approach the lower end thereof, until their 25 distance apart is equal to the length of each of the rows of tablets which the boxes to be filled are designed to receive. Thereafter for a short distance the lower portions of the side members 31 are parallel (Fig. 4), and as shown in Fig. 8, may be moved to- 30 ward or from each other by means of adjusting screws 31^a to accommodate different thicknesses of tablets. The lowest parts of the side members 31 are connected by a tablet retaining plate 32^a which is rigidly at- 35 tached to one of said members and movably engaged with the other, so as to permit of said adjustment.

Mounted within and fixed to the bottom of the trough 30 is a series of parallel, relatively thin vertical plates 32 of which that lying in the middle longitudinal plane of the trough is the longest, (Fig. 7). The plates on either side of this middle plate successively decrease in length until the shortest 45 terminates in the neighborhood of the point of junction of the upper part of the side 31 with the inclined portion which forms its continuation. It will be noted that the design of the side members of the trough 30 and the lengths and proportions of the division plates 32 will depend upon the dimensions of the tablets to be assembled and condensed into rows, although it must be such as to prevent one or more of the tablets of any row getting between any two of the tablets of a lower row and thus wedging or jamming so as to prevent their downward flow or movement under the action of gravity.

60 It is noted that there is such a number of the plates or partitions 32 as to provide the same number of lines of movement for tablets in an edgewise position, as there are tablets to be placed in each box to be filled,

and in the present instance there are eighteen 65 such feeding channels. By means hereafter described, the lowermost lines or rows of assembled tablets are successively removed and the inclination of the delivery trough 30 is such that after each such removal, the 70 mass of tablets therein moves downwardly for a distance equal to the length of an edge of one of the tablets. The partitions or plates 32 of the condensing-trough have their upper ends curved concentrically with the 75 pivot or hinge pin 22 as well as with the plates 26 and 27, which lie respectively in the same planes as said plates 32 and have their adjacent ends undercut (also preferably concentrically with the hinge pin 22) so 80 as to respectively receive the ends of the plates 32 when the container 19 is oscillated on said hinge pin.

By means of this tablet assembling and condensing mechanism successive rows or 85 lines of tablets are delivered to the lower end of the trough 30, where the lowermost row is brought to rest on the surface of a cylindrically curved plate 33 which passes under the lower end of said trough and at 90 one edge terminates immediately adjacent a rotating magazine 34. Concentric with the curved surface of the plate 33 I provide a cross shaft 38 properly supported in bearings in the side members 14 of the frame 95 and carrying two parallel arms 35 connected at their outer ends by a cross bar 36 whose innermost edge is parallel with and immediately adjacent the outer curved surface of the plate 33. Mounted on and extending 100 rearwardly from this cross bar 36 is a second curved plate 37 whose outer surface is preferably spaced away from the outer surface of the first plate 33, with which it is parallel, by a distance substantially equal to the 105 width or breadth of one row of tablets, so that when the shaft 38 is actuated to move the arms 35 with the cross bar 36 and plate 37 toward the magazine 34, said plate and bar carry with them the lowermost row of 110 tablets indicated at α and slidably support the next lower row, which is held by the bridge piece 32^a from being drawn out when the first row is removed. For oscillating the shaft 38 I provide it with a crank arm 115 39 connected to any suitable source of power, whereby under operating conditions it is periodically actuated.

The magazine 34 consists of a wheel-like structure rotatably mounted in any suitable 120 manner and having in its peripheral surface a series of transversely elongated recesses of substantially square section designed for the reception of boxes to be filled. The mechanism for inserting these boxes and lining them with paper, periodically actuating the magazine, etc., forms no part of the present invention, being described and claimed in 125

an application for U. S. patent filed by me April 1, 1913, Serial No. 758,287, of which this application is a division.

From Figs. 9 and 10, it will be seen that each of the arms 35 on the shaft 38 has fixed to it, adjacent said shaft, a radially extending spring strip 72, on whose outer end is fixed a beveled block 73 projecting over the adjacent end of the curved plate 37. The beveled portions of these blocks are so placed that when said plate occupies the position shown in Fig. 10, with its front edge to the rear of the plane of the bottom of the delivery trough 30, said blocks engage the sides 31 of said trough and thereby separate the strips 72. These latter carry forwardly projecting spring fingers 74 which are thus temporarily moved apart so that a row of tablets is free to slide between them on to the fixed curved plate 33.

As the shaft 38 is turned to move the plate 37 toward the magazine 34, the beveled blocks 73 are moved out of engagement with the sides of the trough, thereby permitting the spring strips 72 to press the fingers 74 into engagement with the row of tablets, and hold them in a line as they are moved over the fixed plate 33.

Under operating conditions the magazine 34 is intermittently turned through a predetermined arc equal to the angular distance between the center lines of two adjacent box holding recesses, and is locked from turning while it is not in movement, by suitable mechanism (not shown).

Tablets of the proper size are delivered in quantity to the table 6 and after passage over the perforated plate 7 for the purpose of removing dust and small broken pieces, are fed to the open end of the fixed chute 9, from which they pass into the hollow arm or conduit 20 into the sorting and assembling container 19. As heretofore described, this latter is continuously oscillated on its hinge 22 by the connecting rod 18, so that the mass of irregularly disposed tablets is alternately caused to slide from one end of said container to the other.

Obviously, however, when said tablets strike the upwardly projecting edges 28 of the strips or partitions 27, certain of them are necessarily tilted from a horizontal to an inclined position, and partly under the action of gravity as well as a result of the movement of the container, they fall between these strips, sooner or later assuming edgewise or vertical positions. As the container 19 is moved from the position shown in Fig. 3 to that shown in Fig. 1, all of those tablets which have assumed edgewise positions and are resting on the bottom of the supplementary or assembling trough 25, slide toward the hinge 22 under the false bottom 24, and more or less of them pass

into the guideways formed by the strips or partitions 32 of the delivery trough 30. It may be noted that the end of the assembling trough 25, farthest away from the hinge 22, is preferably perforated or slotted at one end as indicated at 29^a to permit of the escape of dust and small particles of broken tablets.

The tablets delivered to the trough 30 (Fig. 7), slide down the guideways therein until the lower and middle portions of said trough are filled with horizontally extending rows of tablets, though if desired, in starting the machine, this trough may be manually filled with tablets in the positions indicated in dotted lines, and thereafter the continued oscillation of the container 19 will at all times maintain the guideways filled.

In the operation of the machine, the tablets are removed from the lower end of this delivery or condensing trough 30 in successive rows, and each time a row is removed, all of the remaining tablets move downwardly a distance equal to the length of the side of one tablet, it being noted that the various strips or partitions 32 so direct the tablets that as they move down, they are gradually caused to approach each other until, after passing the longest and central partition, they lie in compact rows without intervening spaces. With my peculiar construction and arrangement of the partitions, the tablets at the outer ends of each row are first brought into engagement with each other and as they move down, the partitions are gradually omitted beginning with the outermost pairs, until finally the two middle tablets of the row are allowed to engage each other, thus completing the condensing of said row.

The lowermost row of tablets in the trough 30 rests directly upon the upper surface of the fixed curved plate 33 (Fig. 9), and at the beginning of a cycle of operations, the movable plate 37 lies to the rear of this row. Thereafter when this plate is moved toward the magazine by its operating mechanism, this bottom row of tablets is moved from under the next upper row (which is held from displacement by the bridge piece 32^a) and is thereafter immediately clamped in a horizontal column by the spring fingers 74, so that its constituent pieces maintain a perfect alignment. By the movement of this plate, the row of tablets is finally delivered into the magazine, it being noted that as said plate thus moves, its curved top serves to prevent the succeeding row from falling. The spring fingers 74 remain in gripping engagement with the tablets as these are moved forward and the outwardly curved ends of said fingers slide over the ends of the box in the magazine while the tablets enter the same. As the

plate is returned to its initial position, after having delivered a row of tablets, the beveled blocks 70 strike the sides 31 of the delivery trough moving the spring strips 72 5 with the fingers 74 away from each other so that when the plate reaches its extreme rear position, the row of tablets heretofore held up by it is permitted to freely drop on to the plate 33; the various series of tablets in 10 the trough immediately moving downwardly as above described.

It is to be understood that while in the foregoing description I have referred to tablets as the articles assembled and placed 15 in boxes or packages carried by the magazine, bodies having other forms may be operated on without departing from or essentially modifying my invention. In some cases single objects having the overall dimensions of a row of tablets may be placed 20 in the magazine or boxes carried thereby.

I claim:—

1. Tablet assembling mechanism including a pivotally mounted container having 25 a side opening adjacent its pivot; a receiving conduit connected to said opening; a series of partitions in the container forming tablet collecting channels; means for receiving the tablets from said channels; and 30 means for oscillating the container on its pivot.

2. Tablet assembling mechanism including an oscillatory container having a portion of its bottom cut away and provided 35 with a supplementary tablet receiving extension under said bottom; a series of substantially parallel partitions in said extension placed to receive tablets from the body of the container; and a condensing trough 40 placed to receive tablets collecting in the channels formed by the partitions; with means for alternately moving the container into and out of a position in which tablets pass from it into said condensing trough.

45 3. An oscillatory container having a supplementary extension to its bottom and provided with a cover for a part of said extension; substantially parallel partitions mounted in the said extension and project-

ing to varying heights in the container; 50 with means for receiving rows of tablets from the channels formed by said partitions when said container is moved in one direction.

4. Tablet assembling mechanism including 55 an oscillatory container; a series of partitions mounted therein to form tablet receiving channels, the height of certain of said partitions increasing abruptly from one end and thereafter gradually decreasing to 60 the other end; with means for receiving rows of tablets from the channels formed by said partitions.

5. Tablet assembling mechanism including 65 an oscillatory container; a series of partitions mounted therein to form tablet receiving channels, the height of certain of said partitions increasing abruptly from one end and thereafter gradually decreasing to 70 the other end; and means for receiving rows of tablets from the channels formed by said partitions; the abruptly inclined ends of said partitions being disposed alternately adjacent opposite ends of the container.

6. The combination of a carrier for 75 empty boxes; tablet assembling mechanism including an inclined delivery trough; a curved plate extending upwardly from the trough to the carrier; and an oscillatory member supported concentrically with the 80 curved plate for successively transferring rows of tablets from the trough to boxes in the carrier.

7. Tablet assembling mechanism including 85 a feed chute; an oscillatory container; a conduit connected to deliver to the container in the general line of the axis of oscillation of the latter and having sliding engagement with said chute; and means in the container for arranging the tablets in 90 lines when said container is moved.

In testimony whereof, I have signed my name to this specification, in the presence of two subscribing witnesses.

JOSEPH PERCY REMINGTON.
